US00D551186S

(12) United States Design Patent (10) Patent No.: US D551,186 S
(45) Date of Patent: * Sep. 18, 2007

(54) LCD TELEVISION

(75) Inventors: Jun-Ho Yang, Seoul (KR); Baek-Ki Kim, Seoul (KR)

(73) Assignee: Samsung Electronics Co., Ltd., Kyunggi-do (KR)

() Term: 14 Years

(21) Appl. No.: 29/236,966

(22) Filed: Aug. 24, 2005

(51) LOC (8) Cl. 14-03

(52) U.S. Cl. D14/126

(58) Field of Classification Search D14/125-134, D14/239, 371, 136, 374-377; 312/7.2; 348/836, 348/838, 180, 184, 325, 739; 341/12; 248/917-924, 248/465; 345/104, 133, 156, 168, 87, 173; 720/605, 669, 600, 655; 369/99, 197; 455/344-347
